POWER TOOL

Walter Hall, Los Angeles, Calif., assignor of one-half to J. Michael O'Meara, Los Angeles, Calif.

Application June 26, 1935, Serial No. 28,528

20 Claims. (Cl. 192—150)

This invention relates to power driven devices and relates more particularly to portable power driven tools such as power wrenches, power drills, power screw drivers, etc. A general object of this invention is to provide a power tool such as a power wrench having a simple, practical and effective automatic control clutch.

Power wrenches, etc. are widely used in assembling plants for tightening down bolts, screws, nuts, etc. in fastening together and assembling machine parts. Power wrenches commonly embody an electric motor governed by a switch under the control of the operator and a releasable clutch between the motor shaft and the driven tool carrying spindle that releases when the screw, bolt, nut or the like is tightened down. In assembling plants and the like there is usually a great amount of noise and the operator of a power wrench does not always hear the sound produced by the clutch teeth or clutch parts slipping one past the other following the release of the clutch of his tool, with the result that the clutch parts are allowed to ratchet or slip past one another for a considerable period following the release of the clutch. This subjects the clutch parts to excessive wear and consumes or wastes considerable time. Further, care and skill are required in the operation of a typical power wrench as the clutch must release against the weight of the wrench and the inward pressure exerted on the tool by the operator and in the event that the operator maintains an inward pressure on the tool of too great a magnitude the threads of the nut or other securing part being tightened down may be stripped before the clutch is allowed to release.

Another object of this invention is to provide a power tool such as a power wrench embodying an automatic motor controlling clutch between the driving shaft and the driven tool-carrying spindle that automatically de-energizes the motor when it releases upon tightening down of the nut or securing member, thus preventing excessive wear of the clutch parts and conserving time.

Another object of this invention is to provide an automatic circuit controlling or motor controlling clutch embodied in a simple compact attachment for application to or use on a power wrench of the class now in general use.

Another object of this invention is to provide an attachment for a power tool that embodies an automatic clutch for controlling the motor of the tool which attachment may be easily applied to a typical power wrench with but little

modification or alteration of the wrench structure.

Another object of this invention is to provide a power tool that is operable to tighten down a securing member to a definite degree of tightness and therefore does not require that the operator employ great skill or care in its operation.

Another object of the invention is to provide a power tool such as a power wrench that embodies a clutch between the driving shaft and tool-carrying spindle that automatically releases when the nut or other securing member offers a definite resistance to rotation, said release of the clutch being entirely irrespective of and independent of the inward pressure which the operator may maintain on the tool.

Another object of this invention is to provide a power tool of the character mentioned in which the torque controlled clutch controls the driving motor operating to automatically de-energize the motor when it releases under the torque resulting from the resistance offered by a securing member which has been tightened down to the proper degree of tightness.

A further object of this invention is to provide a power tool of the character mentioned in which the torque controlled clutch for de-energizing the motor may be adjusted to release under any selected torque whereby the tool may be made to tighten down the nuts or securing members to any selected definite degree of tightness.

The various objects and features of my invention will be fully understood from the following detailed description of typical preferred forms and applications of my invention, throughout which description reference is made to the accompanying drawings, in which:

Fig. 1 is a side elevation of one form of the present invention showing the clutch and the adjacent parts in longitudinal cross section. Fig. 2 is a transverse detailed sectional view taken substantially as indicated by line 2—2 on Fig. 1. Fig. 3 is an enlarged fragmentary transverse detailed sectional view taken as indicated by line 3—3 on Fig. 1. Fig. 4 is a fragmentary side elevation of a portion of the wrench showing the clutch and the adjacent parts in longitudinal cross section with the clutch in engagement and illustrating in a diagrammatic manner the electric circuit embodied in the tool. Fig. 5 is a side elevation of a power tool with the attachment provided by this invention provided thereon illustrating the attachment and the adjacent parts of the tool in longitudinal cross section showing the clutch in the released condition. Fig. 6 is a

transverse detailed sectional view taken as indicated by line 6—6 on Fig. 5. Fig. 7 is an enlarged fragmentary detailed sectional view taken as indicated by line 7—7 on Fig. 5 and Fig. 8 is a fragmentary side elevation showing the clutch in the engaged condition illustrating the attachment in longitudinal cross section and diagrammatically illustrating the motor circuit.

The form of the present invention illustrated in Figs. 1 to 4, inclusive, of the drawings, includes, generally, a housing or body 10 containing a motor M for operating a shaft 11, a spindle 12 carrying a socket 13 or other suitable means for engaging a securing member, an automatic releaseable clutch 14 between the shaft 11 and the spindle 12, and a control 15 for the motor M operatively associated with the clutch 14.

The body 10 is provided to encase the operating motor M and the reduction drive (not shown) usually employed in power tools of this class. The body 10 has a main part 16 for enclosing the motor M and a reduced forward part 17 which may be considered as enclosing the reduction gearing (not shown). The present invention is not primarily concerned with the character or details of the motor M or the reduction gearing and these elements have been omitted from the present disclosure as they are well known to those skilled in the art. A suitable handle 18 is provided at the rear or outer end of the body 10 and conductors 19 and 20 carrying the current for energizing the motor M may enter the tool through the lower end portion of the handle 18. The shaft 11, which is driven by the motor M through the reduction gearing (not shown) projects from the forward end of the reduced body portion 17. In the preferred arrangement illustrated the shaft 11 is co-axial with the body 10.

The spindle 12 is provided to carry the socket 13, a screw driver bit, or other device for non-rotatably engaging a securing member to be tightened by the tool or wrench. In the particular application of the invention illustrated in the drawings the socket 13 is fixed to the outer or forward end portion of the spindle 12 to engage or receive a nut, the head of a bolt, stud, screw, or the like. The spindle 12 is co-axial with the shaft 11 and body 10 projecting forwardly from a point spaced from the forward end of the shaft 11. The tool-carrying spindle 12 may be cylindrical and may be of any suitable or desired length.

The clutch 14 is provided to transmit rotation from the shaft 11 to the spindle 12 when the socket 13 is engaging a nut or securing member and the operator is maintaining a suitable inward pressure on the wrench. The clutch 14 is an important feature of the invention as it is adapted to automatically release when the securing member has been tightened to a selected degree of tightness, its release causing actuation or opening of the control 15 and its release being entirely irrespective of the inward pressure maintained on the tool by the operator.

In accordance with the invention the automatic clutch 14 includes two members 21 and 22 axially shiftable into and out of rotation transmitting cooperation, one member being on the shaft 11 and the other member being shiftable on the spindle 12. In the particular form of the invention illustrated in the drawings the clutch member 21 is fixed to the shaft 11 and the clutch member 22 is shiftably carried by the spindle 12. As shown in the drawings, the member 21 is integral with the shaft 11, it being understood

that the member 21 may be a separable part suitably fixed or attached to the shaft. The clutch member 22 has a sleeve portion 23 surrounding and shiftable on the spindle 12 to turn therewith and to be shiftable longitudinally thereon. In the simple form of the invention illustrated in the drawings a key 24 cooperates with grooves or key-ways in the spindle 12 and member 22 to connect the member with the spindle for rotation and relative longitudinal movement. A flange or head 25 is provided on the inner end of the spindle 12 and is adapted to cooperate with or fit a socket 26 in the member 22 to limit the inward or rearward movement of the clutch member on the spindle. The clutch members 21 and 22 have axially projecting parts 27 on their opposing ends or sides. The parts 27 are adapted to mesh or interlock to connect the spindle 12 with the shaft 11 for rotation by the shaft. The engaging sides or faces 28 of the clutch parts 27 are bevelled or pitched so that they tend to slip one on the other when subjected to torque. The outer edges of the cooperating clutch parts 27 are preferably chamfered or bevelled.

The clutch 14 includes yieldable means for urging the member 22 rearwardly or toward the clutch member 21. A longitudinally adjustable collar 30 surrounds the spindle 12 and is adapted to be releasably locked or set in a selected position by a set screw 31 or equivalent means. A spring 32 surrounds the spindle 12 and is under compression between the collar 30 and a washer 33 bearing on the outer end of the sleeve portion 23 of the clutch member 22. The spring 32 operates to normally hold the clutch member 22 in a position where the bottom wall of its socket 26 engages the head 25. In accordance with the invention the shaft 11 and the spindle 12 are related for limited relative longitudinal movement whereby the engagement of the clutch parts 27 of the clutch members 21 and 22 is accomplished by the operator moving the body 10 inwardly when the socket 13 is in engagement with a nut or securing member.

The clutch 14 includes a slack connection between the shaft 11 and the spindle 12 whereby the shaft 11 may be moved forwardly relative to the spindle 12 to engage the clutch parts 27. The clutch member 22 carries a tube or sleeve 34 which projects from the active end of the clutch member to surround the clutch member 21. The sleeve 34 may be threaded or otherwise attached to the periphery of the member 22. An inwardly projecting annular flange 35 is provided on the inner end of the sleeve 34 and is adapted to engage the inner or rear surface of the clutch member 21 to limit the relative axial movement between the shaft 11 and the spindle 12 in one direction. The forward faces of the clutch parts 27 on the member 21 are adapted to engage the face of the head 25 to limit the relative longitudinal movement between the shaft 11 and the spindle 12 in the other direction. The sleeve 34 and its flange 35 may have sliding bearing cooperation with the clutch member 21 to assist in carrying and steadyng the spindle 12.

A reduced stem 36 projects rearwardly from the head 25 and is slidably in a central socket 37 in the shaft 11. A spring 38 is arranged under compression between opposing parts or faces on the shaft 11 and the spindle 12 to normally yieldingly hold the spindle in an out position where the clutch parts 27 are disengaged and the flange 35

35 engages the rear surface of the member 21. In the particular form of the invention shown in the drawings the spring 38 is arranged in the socket 37 under compression between the end of the stem 36 and the bottom wall of the socket. The spring 38 is preferably weaker than the spring 32 for the reason to be hereinafter described. The spring 32 normally holds the clutch member 22 in a position where the bottom wall 13 of its socket 26 engages the head 25 and the spring 38 normally holds the spindle 32 in a position where the clutch parts 27 are disengaged and the flange 35 engages the rear surface of the clutch part 21. When the socket 13 is engaged 15 with a nut or securing member the operator pushes inwardly on the handle 18 to compress the spring 38 and move the body 10 and the shaft 11 inwardly bringing the clutch parts 27 against one another or in meshing engagement. In the event that the clutch parts 27 on the members 21 and 22 do not come into mesh the operator 20 partially turns or rocks the body 10 to bring the clutch parts 27 into proper meshing engagement. When the clutch parts 27 are in meshing or interlocking engagement the parts 27 of the clutch member 21 cooperate with the parts 27 of the clutch member 22 to transmit rotation from the shaft 11 to the spindle 12.

The control for the motor M is associated with 30 and operated by the clutch 14 to automatically de-energize the motor M when the clutch 14 releases under torque caused by resistance to rotation of the spindle 12 offered by a tightened down securing member with which the socket 13 is engaged. The motor M is adapted to be energized or operated by electric current carried by the conductors 19 and 20. One lead of the energizing circuit, say the conductor 20, may be connected to one side or post of the motor M. A conductor 40 extends from the other post of the motor M to a binding post or screw 41 on the forward end of the reduced body part 17. The second conductor or lead 19 of the energizing circuit extends through the body 10 to a post or screw 42 on the forward end of the body part 17. The control 15 includes contacts 43 connected with or carried by the screws 41 and 42. The contacts 43 comprise flexible straps or members having base flanges 44. The flanges 44 are 45 provided with longitudinal slots 45 receiving the screws 41 and 42. The screws 41 and 42 secure the contacts in position while the slots 45 allow the contacts to be adjusted toward and away from the longitudinal center of the tool when the screws are loosened. The contacts 43 and the screws 41 and 42 are suitably insulated from the body part 17 by blocks 9 of insulation. The contacts 43 project axially or forwardly from their bases 44 and are provided at their outer 50 ends with spherical parts or heads 46.

An annular or tubular extension 47 is threaded on the inner end of the sleeve 34 and has an inwardly projecting annular flange 48. The inner surface of the flange 48 is bevelled or inclined 55 rearwardly and outwardly relative to the longitudinal axis of the tool. The particular control 15 illustrated includes a ring contact 50 which may be rotatably carried between the flange 35 and the flange 48. In the construction shown 60 in the drawings spaced stems 8 project from the end of the body part 17 and cooperate with or are engaged by the ring contact 50 to hold the contact against rotation. The periphery and sides of the ring contact 50 are provided with 65 insulation or these surfaces of the contact bear 70 on a lining 49 of suitable insulation. A groove 51 is provided in the internal wall or side of the ring 50. The groove 51 has spherically concaved walls and is adapted to receive the substantially spherical heads 46 of the contacts 43. The contact 50 is, of course, formed of conducting material and constitutes a bridge between the conductors or lines 19 and 40 when it is in the position where its groove 51 receives the contact heads 46. The insulating lining 49 preferably covers 10 the inclined face of the flange 48. The contacts 43 are positioned and formed so that their heads 46 are engaged by the lining 49 on the inclined face of the flange 48 upon inward movement of the body 10 relative to the spindle 12 and this engagement results in inward flexing of the contact 43 so that the heads 46 snap into the groove 51 and remain in proper bearing contact with the wall of the groove through the outward pressure exerted by the resilient contacts. 15

The control 15 includes a manual switch 52 connected in one of the energizing lines or conductors 19 or 20. In the particular case illustrated in the drawings the switch 52 is provided in the line 19. The switch 52 includes a spring 25 53 which normally acts to hold the switch in its open position. The switch 52 includes a handle or trigger 54 whereby it may be readily closed by the operator of the wrench. The trigger 54 projects from the inner side of the portion of 30 the handle 18 gripped by the user's fingers so that the user engaging the handle 18 has full control over the switch 52. It will be apparent how the user may easily depress the trigger 54 to close the switch 52. The control 15 may include a 35 second manual switch 55 provided in a line 56 to shunt past the switch 52. The switch 55 which may or may not be employed is located for convenient engagement by the operator and is such that it may be operated to a closed position 40 to remain closed until deliberately opened so that the operation of the wrench may be automatic or completely under the control of the clutch 14. A protective shell 58 may be secured to the reduced body portion 17 and may extend forwardly 45 to telescope over the extension 47 and thus enclose the space between the body portion 17 and the extension and protect the contacts 43 and the adjacent parts. 50

In operation assuming the switch 55 to be open and the socket 13 to be in engagement with a nut or the head of a securing member, the operator gripping the handle 18 depresses the trigger 54 and applies an inward pressure on the handle to move the body 10 inwardly. The engagement of the socket 13 with the nut or securing member of the work holds the spindle 12 against longitudinal movement. Accordingly, the inward movement of the body 10 results in compression of the spring 38 and movement of 60 the clutch member 21 toward the clutch member 22 bringing the clutch parts 27 of the two members into cooperation. In the event that the clutch parts 27 do not mesh or interlock the operator may partially turn or rock the body 10 bringing the clutch members to positions where their clutch parts 27 come into meshing cooperation. During the inward movement of the body 10 into engagement of the clutch parts 27 the heads 46 of the contacts 43 are moved inwardly on the insulation lining 49 covering the inclined face of the flange 48 and forced inwardly through this engagement until they are in positions to snap into the groove 51 of the ring contact 50. The resiliency of the contacts 43 in- 75

sures the proper engagement of the heads 46 in the groove 51. Snapping of the contact heads 46 into the groove 51 of the bridge contact or ring contact 50 completes the energizing circuit to the motor M so that the motor is automatically energized.

Operation or energization of the motor M of course results in rotation of the shaft 11 and the parts 27 of the clutch member 21 cooperate with the parts 27 of the clutch member 22 to transmit rotation from the shaft 11 to the spindle 12. The operator may maintain a suitable or desirable inward pressure on the handle 18 as the motor operates to turn the spindle 12 and thus tighten down the nut or securing member engaged by the socket 13. The inward pressure exerted by the spindle on the handle 18 of course must be sufficient to overcome the spring 38 and maintain the clutch member 21 in proper engagement with the clutch member 22. In practice the spring 38 may be comparatively light and easily compressed. As the nut or securing member is tightened down it offers increased resistance to rotation of the spindle 12. Upon the nut or securing member being tightened down to a definite or predetermined degree of tightness it offers such resistance to rotation of the spindle 12 that the torque imposed on the contacting clutch parts 21 overcomes the frictional cooperation between their sloping faces 28 and overcomes the pressure exerted by the spring 32 and results in outward movement of the clutch member 22 on the spindle 12. This outward movement of the clutch member 22 of course disengages the clutch parts 21. Outward movement of the clutch member 22 on the spindle 12 caused by the release of the clutch parts 21 moves the ring contact 50 outwardly disengaging it from the contact heads 46 breaking or opening the energizing circuit to the motor M. Thus the release of the clutch C causes opening of the motor circuit and de-energization of the motor. Accordingly, the rotation of the shaft 11 stops substantially simultaneously with the disengagement of the clutch C so that the clutch parts are not subjected to excessive wear. As soon as the motor M is automatically de-energized by the disengagement of the clutch 14 the operator may relieve the pressure on the trigger 54 to allow the switch 52 to open and may relieve the inward pressure on the wrench and disengage the socket 13 from the nut or securing member.

From the above it will be noted that the disengagement or release of the clutch member 22 from the clutch member 21 is entirely automatic and independent of the inward pressure exerted on the wrench by the operator. The inward pressure put on the wrench by the operator is transmitted from the shaft 11 to the spindle 12 by the engagement of the outer faces of the clutch parts 21 on the clutch member 21 with the face of the head 25. This engagement of the parts 21 with the head 25 in no way affects the disengagement of the clutch 14. As the control 15 is operated or governed by the clutch 14 to open the motor circuit simultaneously with the disengagement of the clutch 14 the motor is automatically de-energized simultaneously with the opening of the switch so that no time is lost following the disengagement of the clutch. The wrench may be adjusted or regulated to tighten down the securing members to any selected or desired degree of tightness by loosening the set screw 31 and adjusting the collar 30 longitudinally 75 on the spindle 12. Longitudinal adjustment of

the collar 30 of course adjusts or regulates the pressure exerted on the clutch part 22 by the spring 32 determines the torque under which the clutch 14 releases and thus determines the degree to which the wrench tightens down the securing members before the motor M becomes de-energized. If the operator closes the switch 55 and leaves it closed during the operation of the wrench, the motor M is governed solely by the control 15. In other words, the inward movement of the body 10 relative to the spindle 12 when the socket 13 is in engagement with a securing member moves the contacts 46 into engagement with the ring 50 to automatically energize the motor M and the release of the clutch 14 as described above results in de-energization of the motor M. As the operation of the wrench may be entirely automatic or under the control of the clutch 14 and the control 15 the operator may leave the switch 55 closed, if desired. 20

The form of the invention illustrated in Figs. 5 to 8, inclusive, of the drawings, is in the nature of an attachment for a power tool or wrench T. The tool T which is typical of wrenches and tools of this class includes a body 60 enclosing an electric motor 61 and a suitable speed reduction gearing (not shown). The reduction gearing is provided in a reduced forward portion 62 of the body 60 and the shaft 63 driven by the motor 61 through the gearing projects from the forward end of the forward portion 62. The wrench or tool T further includes a spindle 64 carrying a screw driver bit, a socket 65 or other means for engaging screws, nuts, bolts or the like. A releasable clutch is provided between the shaft 63 and the spindle 64. The clutch comprises two clutch members 66 and 67. The member 66 is integral with the shaft 63 and the member 67 is integral with the spindle 64. Clutch parts 68 are provided on the opposing faces of the members 66 and 67 to mesh or interengage for the transmission of rotation from the shaft 63 to the spindle 64. The engaging faces or sides 68a of the parts 68 are pitched and tend to disengage when the sides are under torque. A reduced stem 69 on the rear end of the spindle 64 or its clutch member 67 is slidably in a central socket 70 in the shaft 63. A spring 71 is provided in the socket 70 and is under compression between the bottom of the socket and the end of the stem 69 to normally yieldingly urge the spindle 64 to an out position where the clutch parts 68 are disengaged. A handle 72 is provided on the rear or outer end of the body 60 to facilitate the manipulation of the tool. The motor 61 is adapted to be manually controlled by a switch 73 connected in one lead 74 of the motor circuit 74-75. The switch 73 includes a spring 76 which normally holds it in the open position and includes a trigger 77 projecting from the forward side of the portion of the handle 72 gripped by the operator's fingers. The structure of the tool T described above may be considered as typical of the general class of power tools to which the attachment of the invention is applicable. 65

The attachment provided by the present invention illustrated in Figs. 5 to 8, inclusive, of the drawings, includes, generally, spaced contacts 78 connected in the motor energizing circuit 74-75, a sleeve 79 carried by the spindle 64 70 and a ring contact 80 carried by the sleeve 79 and engageable by the contacts 78 to complete the circuit to the motor 61.

The contacts 78 are preferably mounted on or attached to the forward end of the body portion 75

62 at spaced points. They are shown at diametrically opposite sides of the shaft 63. The contacts 78 may be carried by blocks 81 of insulation secured to the body portion 62 in any suitable manner. The contacts 78 are flexible strap-like members each having a base flange 82 seated on an insulation block 81. Screws 83 threaded into openings in the blocks 81 pass through slots 84 in the flanges 82 to adjustably attach the contacts 78 to the blocks. When the screws 83 are loosened the contacts 78 may be adjusted toward and away from the longitudinal axis of the tool T. The contacts 78 project outwardly from their base flanges 82 and are provided at their outer ends with spherical heads 85. The leads or conductors 74 and 75 of the motor energizing circuit may be electrically connected with the contacts 78 in any suitable manner. In the particular case illustrated in the drawings the conductors 74 and 20 75 are wrapped on or soldered to the screws 83 to be electrically connected with the contacts 78. The conductors 74 and 75 are preferably trained over the exterior of the tool body 60 and its reduced forward portion 62 to the conductors 78 so that it is unnecessary to disturb the interior of the tool to provide for the arrangement of the conductors on the tool.

The sleeve 79 is provided to carry or support the ring contact 80. The sleeve 79 replaces the means originally provided on the tool T for connecting the spindle 64 with the shaft 63 for longitudinal movement relative to the shaft. In accordance with the invention the sleeve 79 is secured to the clutch member 67 of the spindle 64. 35 The sleeve 79 surrounds the member 67 and projects rearwardly therefrom to surround and slidably engage the periphery of the clutch member 66. The sleeve 79 may be fixed to the clutch member 67 in any suitable manner, for example, 40 it may be welded to the member 67 as at 86. An inwardly projecting annular flange 87 is provided on the rear end of the sleeve 79 and is adapted to engage the rear face of the clutch member 66 to limit relative longitudinal movement between the shaft 67 and the spindle 64 in one direction. An extension 88 is threaded on the rear end portion of the sleeve 79 to project rearwardly from the sleeve. The extension 88 has an inwardly projecting annular flange 89 45 spaced from the flange 87 to leave or provide an annular groove 90. The internal surface 91 of the flange 89 is inclined outwardly and rearwardly as clearly illustrated in Figs. 5 and 8 of the drawings. A protective sheath or shell 99 50 may be provided on the reduced portion 62 of the tool body 60 to extend forwardly and telescope over the extension 88 of the sleeve 79 and thus enclose or surround the space between the extension 88 and the forward end of the body. 55 The ring contact 80 is engageable by the contacts 78 when there is inward movement of the tool body 60 relative to the spindle 64 to form a conducting bridge or connection between the contacts 78 and thus complete the circuit to the driving motor 61. The ring contact 80 is formed of a suitable conducting material and is rotatable or free to float in the groove 90. The groove 90 has a lining 92 of insulation to prevent engagement of the contact 80 with the flange 87 or the extension 88. The lining 92 of insulation continues rearwardly to extend over and cover the inclined surface 91 of the flange 89 so that the heads 85 of the contacts 78 cannot engage the surface 91 simultaneously with their engagement with the ring contact 80. An annular groove 93

is provided in the interior or internal surface of the ring contact 80. The groove 93 has a spherically concaved wall and is proportioned to effectively receive the spherical heads 85 of the contacts 78.

If desired or found practical a manual switch 94 may be connected in a line 75 to shunt out the switch 73. The switch 94 is such that it may remain in either the open or closed condition until deliberately shifted or operated by the user of the tool. The switch 94 may be an original element of the tool T or may be applied to the tool when the attachment is embodied in the tool.

It is believed that it will be apparent how the contacts 78 may be easily and quickly attached to the forward end of the body portion 62 and properly connected in the motor circuit. The sleeve 97 carrying the extension 88 the contact ring 80 and the shell 91 may be easily and quickly attached to the clutch member 69. The attachment of the invention is such that it may be readily applied to or embodied in the power tool with very little alteration or modification of the original tool structure.

In the operation of the tool T provided with the attachment the operator may prefer to have the switch 94 in its open condition in which case he first engages the socket 65 with the nut, bolt or other securing member and then moves or pushes the tool body 60 inwardly. This inward movement may be accomplished by engaging or grasping the handle 72 and pushing inwardly thereon. As the operator moves the tool body 60 inwardly he may depress the trigger 77 to close the switch 73. The engagement of the socket 65 35 with the securing member or the work holds the spindle 64 against inward or longitudinal movement and as the tool body 60 is moved inwardly the heads 85 of the contacts 78 engage the lining of insulation on the inclined surface 91 and the contacts are flexed inwardly so that their heads 85 may snap into the groove 93 of the contact ring 80. The resiliency of the contacts 98 holds their heads 85 in proper engagement with the wall of the groove 93. The engagement of the contact 40 heads 85 with the contact ring 80 completes the energizing circuit to the motor 61. The inward movement of the tool body 60 relative to the spindle 64, as described above brings the clutch parts 68 into meshing or interlocking engagement substantially simultaneously with the cooperation of the heads 85 with the contact ring 80. Thus the spindle 64 is clutched with the shaft 63 substantially simultaneously with the energization of the motor 61.

Rotation of the spindle 64 by the motor 61 driving through the shaft 63 and the clutch causes the nut, bolt or other securing member to be turned down or tightened. When the securing member has been tightened to a suitable degree 60 of tightness the inclined cooperating faces 68^a of the contact parts 68 slip and disengage under the increased torque causing the shaft 63 and the tool body 50 to move or kick rearwardly. This movement of the shaft 63 and the tool body 60 65 of course releases the clutch and is accompanied by disengagement of the contact heads 85 from the contact ring 80 so that the motor 61 is de-energized substantially simultaneously with the disengagement or release of the clutch. Thus the 70 motor of the power tool T is automatically de-energized when the nut or securing member has been tightened to the desired degree of tightness so that the clutch parts 68 are not subjected to excessive unnecessary wear and no time is lost 75

in the operation of the tool. If desired, the operator may have the switch 95 in a closed condition during the operation of the tool. When the switch 94 is closed the tool may be operated automatically or without the depression of the trigger 77. With the switch 94 in the closed condition the engagement of the contact heads 85 with the contact ring 80 results in closing of the motor circuit regardless of the condition of the switch 73 so that the tool is automatically energized or actuated by the inward movement of the tool body 60. The contacts 78 may be adjusted radially to insure the proper engagement of their heads 85 with the ring contact 80.

Having described only typical preferred forms and applications of my invention I do not wish to be limited or restricted to the specific details set forth, but wish to reserve to myself any variations or modifications that may appear to those skilled in the art or fall within the scope of the following claims.

Having described my invention, I claim:

1. In a portable power tool having a driving motor and an energizing circuit for the motor, the combination of a driving element driven by the motor, a driven element, a clutch comprising clutch members on the elements, the clutch members being related for relative movement between an engaged rotation transmitting position and a released position and being formed to move one relative to the other to said released position when subjected to a heavy torque, and means normally yieldingly holding the clutch members in the released position, and a control for the motor governed by movement between the clutch members including cooperative contacts movable axially with the clutch members.

2. In a portable power tool having an energizing circuit, the combination of a driving element, a driven element, a clutch comprising clutch members on the elements, the clutch members being related for relative movement between an engaged rotation transmitting position and a released position and being formed to move one relative to the other to said released position when subjected to a heavy torque, and a control for the energizing circuit including contacts in said circuit, one of the contacts being movable axially with one clutch member, the other contact being movable axially with the other clutch member, the contacts being engaged when the clutch members are in the engaged position and disengaged when the clutch members are in the released position.

3. In a portable power tool having an energizing circuit, the combination of a driving element, a driven element, a clutch comprising clutch members on the elements, the clutch members being related for relative movement between an engaged rotation transmitting position and a released position and being formed to move one relative to the other to said released position when subjected to a heavy torque, a spring normally yieldingly holding the clutch members in the released position, and a control for the energizing circuit including a contact in the circuit associated with one element to be movable axially therewith, and a contact in the circuit movable axially with the clutch member on the other element, the contacts being disengaged to open said circuit upon movement of the clutch members to the released position.

4. In a power tool a motor, an energizing circuit for the motor, a driving element operated by the motor a driven element, clutch members on

the elements, the clutch members being related for relative movement between engaged rotation transmitting positions and released positions, parts on the clutch members cooperable when the members are in the engaged positions and shaped to cause relative movement of the members to the released positions when substantial resistance is offered to rotation of the driven element, and contact means operable to open said circuit when the clutch members are moved one relative to the other to the released positions, said means including a contact in said circuit movable axially with one clutch member, and a contact in said circuit movable axially with and rotatably carried by the other clutch member for cooperation with the first mentioned contact.

5. In a portable power tool having a motor and an energizing circuit for the motor, the combination of, a driving element driven by the motor, a driven element, the elements being related for relative axial movement, clutch members on the elements, the clutch members being related for relative movement between engaged rotation transmitting positions and released positions, parts on the clutch members cooperable when the members are in the engaged positions and shaped to cause relative movement of the members to the released positions when substantial resistance is offered to rotation of the driven element, means normally yieldingly holding the clutch members in the released position, and a control for said circuit including contacts connected in the circuit and associated with the elements and the clutch members to come into engagement to energize the motor when the elements are shifted axially one relative to the other to engage the clutch members and to disengage to deenergize the motor when the clutch members are released.

6. In a power tool having a motor and an energizing circuit for the motor, the combination of a driving element driven by the motor, a driven element, clutch members on the elements, the clutch members being related for relative movement between engaged rotation transmitting positions and released positions, parts on the clutch members cooperable when the members are in the engaged positions and shaped to cause relative movement of the members to the released positions when substantial resistance is offered to rotation of the driven element, and a control for said circuit including spaced contacts each connected with a lead of said circuit and mounted to move longitudinally with one of the clutch members, and a contact mounted to move longitudinally with the other clutch member and cooperable with the spaced contacts when the clutch members are engaged and disengaged from the spaced contacts when the clutch members are released.

7. In a power tool having a motor and an energizing circuit for the motor, the combination of a driving element driven by the motor, a driven element, clutch members on the elements, the clutch members being related for relative movement between engaged rotation transmitting positions and released positions, parts on the clutch members cooperable when the members are in the engaged positions and shaped to cause relative movement of the members to the released positions when the part engaged by the socket offers substantial resistance to rotation, and a control for said circuit including spaced contacts each connected with a lead of said circuit and

mounted to move longitudinally with one of the clutch members, and a rotatable ring contact mounted to move longitudinally with the other clutch member and cooperable with the spaced contacts when the clutch members are engaged and disengaged from the spaced contacts when the clutch members are released.

8. In a portable power tool having a driving motor, an energizing circuit for the motor, a driving element driven by the motor, a driven element shiftable relative to the driving element, and cooperable clutch members on the elements releasable under torque to cause relative longitudinal movement between the elements, the combination of spaced contacts connected in the circuit and mounted to move longitudinally with the driving element, and a contact movable longitudinally with the driven element cooperable with the spaced contacts to complete the motor circuit when the clutch members are engaged and disengageable from the spaced contacts to open the motor circuit when the clutch members release.

9. In a portable power tool having a driving motor, an energizing circuit for the motor, a driving element driven by the motor, a driven element shiftable relative to the driving element, and cooperable clutch members on the elements releasable under torque to cause relative longitudinal movement between the elements, the combination of spaced contacts connected in the circuit and mounted on the driving element to move longitudinally with the driving element, a sleeve carried by the driven element, and a contact rotatably carried by the sleeve and cooperable with the spaced contacts to complete the motor circuit when the clutch members are engaged and disengageable from the spaced contacts to open the motor circuit when the clutch members release.

10. An attachment for a power tool having a driving motor, a circuit for energizing the motor, a shaft driven by the motor, a tool spindle, the shaft and spindle being related for relative longitudinal movement and cooperable clutch members fixed on the shaft and spindle releasable under torque to cause relative longitudinal movement between the shaft and spindle, the attachment including a contact adapted to be mounted on the tool to be movable longitudinally with the shaft, means for mounting said contact on the tool free of the shaft the contact being connected in said circuit, and a contact adapted to be mounted on the spindle to move longitudinally therewith and cooperable with the first mentioned contact when the clutch members are engaged and disengageable from the first mentioned contact to open the motor circuit when the clutch members release.

11. An attachment for a power tool having a driving motor, a circuit for energizing the motor, a shaft driven by the motor, a tool spindle, the shaft and spindle being related for relative longitudinal movement and cooperable clutch members fixed on the shaft and spindle releasable under torque to cause relative longitudinal movement between the shaft and spindle, the attachment including a contact adapted to be mounted on the tool to be movable longitudinally with the shaft, the contact being connected in said circuit, a sleeve adapted to be attached to the clutch member on the spindle, and a contact carried by the sleeve to cooperate with the first mentioned contact to close the circuit when the members are engaged and disengageable from

the first mentioned contact to open the circuit when the members release.

12. An attachment for a power tool having a driving motor, a circuit for energizing the motor, a shaft driven by the motor, a tool spindle, the shaft and spindle being related for relative longitudinal movement and cooperable clutch members fixed on the shaft and spindle releasable under torque to cause relative longitudinal movement between the shaft and spindle, the attachment including a contact adapted to be mounted on the tool to be movable longitudinally with the shaft, the contact being connected in said circuit, a sleeve adapted to be attached to the clutch member on the spindle, and a ring contact rotatable in the sleeve and having a groove for receiving the first mentioned contact to close the circuit when the members are engaged, the ring contact being disengageable from the first mentioned contact to open the circuit when the members release.

13. A portable power tool including a body, a motor carried by the body, a circuit for actuating the motor, two rotatable elements related for relative longitudinal movement, one element being a driving element driven by the motor, the other element being a driven element, clutch members on the elements engageable upon relative longitudinal movement between the elements to connect the elements for rotation, means normally yieldingly holding the clutch member out of engagement, a control for the circuit including two contacts one being movable longitudinally with each clutch member, the contacts being cooperable when the clutch members are engaged to complete the circuit, one clutch member being longitudinally shiftable on its element, and engaging parts on the clutch members operable to cause longitudinal shifting of the shiftable member to disengage the contacts when there is heavy resistance to rotation of the driven element.

14. In a portable power tool having a body, a motor carried by the body and a circuit for actuating the motor, the combination of two rotatable elements related for relative longitudinal movement, one element being a shaft driving element driven by the motor, the other element being a driven element, clutch members on the elements engageable upon relative longitudinal movement between the elements to connect the elements for rotation, means normally yieldingly holding the clutch members out of engagement, a control for the circuit including two contacts one being movable longitudinally with each clutch member, the contacts being cooperable when the clutch members are engaged to complete the circuit, one clutch member being longitudinally shiftable on its element, means normally yieldingly resisting longitudinal shifting of the shiftable member, and engaging parts on the clutch members operable to cause longitudinal shifting of the shiftable member to disengage the contacts when there is heavy resistance to rotation of the driven element.

15. In a portable power tool of the character described having a motor and a circuit for actuating the motor, the combination of two rotatable elements related for relative longitudinal movement, one being a driving element driven by the motor, the other being a driven element, clutch members on the elements engageable upon relative longitudinal movement between the elements to connect the elements for rotation, means normally yieldingly holding the clutch members disengaged, one of the clutch members being axially shiftable on its element, means for adjusting said

means, a contact movable longitudinally with each element, the contacts being cooperable when the clutch members are engaged to complete the circuit, and parts on the clutch members operable 5 to cause longitudinal shifting of said member when under torque to disengage the contacts.

16. A portable power tool including a body, a motor carried by the body, a circuit for actuating the motor, two rotatable elements related for 10 relative longitudinal movement, one being a driving element driven by the motor and movable longitudinally with the body, the other being a driven element movable axially relative to the body, clutch members on the elements engageable 15 upon relative longitudinal movement between the elements to connect the elements for rotation, means normally yieldingly holding the clutch members out of engagement, one of the clutch members being axially shiftable on its element, a 20 contact mounted to move longitudinally with one element, a contact carried by the axially shiftable member, the contacts cooperating when the clutch members are engaged to complete said circuit, and cooperating parts on the clutch members operable 25 to cause axial shifting of said members to disengage the members and the contacts when a heavy torque is imposed on the members.

17. A portable power tool including a body, a motor carried by the body, a circuit for actuating 30 the motor, two rotatable elements related for relative longitudinal movement, one being a driving element driven by the motor, the other being a driven element shiftable axially relative to the body, clutch members on the elements engageable 35 upon relative longitudinal movement between the elements to connect the elements for rotation, means normally yieldingly holding the clutch members out of engagement, one of the clutch members being axially shiftable on its element, a 40 contact mounted to move longitudinally with one element, a spring bearing on the axially shiftable member to resist its axial movement, a contact carried by the axially shiftable member, the contacts cooperating when the clutch members 45 are engaged to complete said circuit, and cooperating parts on the clutch members operable to cause axial shifting of said members to disengage the members and the contacts when a heavy torque is imposed on the members.

18. A portable power tool including a body, a motor carried by the body, a circuit for actuating the motor, two rotatable elements related for relative longitudinal movement, one being a driving element driven by the motor, the other being a tool driven element shiftable axially relative to the body, clutch members on the elements engageable upon relative longitudinal movement between the elements to connect the elements for rotation, means normally yieldingly holding the 10 clutch members out of engagement, one of the clutch members being axially shiftable on its element, a contact mounted to move longitudinally with one element, a spring bearing on the axially shiftable member to resist its axial movement, 15 means for regulating the pressure exerted by the spring, a contact carried by the axially shiftable member, the contacts cooperating when the clutch members are engaged to complete said circuit, and cooperating parts on the clutch members 20 operable to cause axial shifting of said members to disengage the members and the contacts when a heavy torque is imposed on the members.

19. In a portable power tool having a driving motor and an energizing circuit for the motor, 25 the combination of, a driving element driven by the motor, a driven element, a clutch comprising, clutch members on the elements related for relative movement between an engaged position and a released position and being formed to move relative to one another to the released position when subjected to heavy torque, a control for the motor circuit governed by movement between the clutch members, and an optional manual switch 30 in said circuit.

20. In a portable power tool having a driving motor and an energizing circuit for the motor, the combination of, a driving element driven by the motor, a driven element, a clutch comprising, clutch members on the elements related for relative movement between an engaged position and a released position and being formed to move relative to one another to the released position when subjected to heavy torque, contact means 40 in said circuit associated with the clutch members 45 to automatically control said circuit, and a manual switch for controlling said circuit at the option of the operator.

WALTER HALL
